United States Patent Office

Des. 185,092
Patented May 5, 1959

185,092

BADGE OR SIMILAR ARTICLE

Walter F. Lyons, North Attleboro, Mass., assignor to
V. H. Blackinton & Co., Inc., North Attleboro, Mass., a corporation

Application May 16, 1958, Serial No. 50,927

Term of patent 14 years

(Cl. D29—2)

The figure is a plan view of a badge showing my new design.

The back is plain and has a conventional fastening means.

The badge is of conventional thickness.

I claim:

The ornamental design for a badge or similar article, substantially as shown and described.
